C. E. KAIL

EGG BEATER

Filed May 2, 1922

INVENTOR

Charles E. Kail

BY

C. E. Beach,

ATTORNEY

UNITED STATES PATENT OFFICE.

CHARLES E. KAIL, OF BINGHAMTON, NEW YORK, ASSIGNEE TO THE A. & J. MANUFACTURING CO., OF BINGHAMTON, NEW YORK, A CORPORATION OF NEW YORK.

EGG BEATER.

Application filed May 2, 1922. Serial No. 557,910.

To all whom it may concern:

Be it known that I, CHARLES E. KAIL, a citizen of the United States, residing at Binghamton, county of Broome, and State 5 of New York, have invented certain new and useful Improvements in Egg Beaters, of which the following is a specification.

This invention relates to egg-beaters, and particularly to hand-operated beaters in 10 which two beater elements may be simultaneously rotated in opposite directions by turning an operating wheel.

An important object of this invention is to provide a beater of the type referred to 15 in which all parts are so formed and arranged that adjacent surfaces thereof may be readily cleaned; so that the beater, as a whole, may be kept in hygienic condition.

20 Another object is to provide such a beater which is more durable than prior beaters, while being lighter and less expensive to manufacture.

A further object is to so relatively arrange 25 the parts of such a beater that it may be more conveniently operated, and so that the parts will be subjected to less strain than prior beaters.

With these and other objects in view, some 30 of which other objects will be obvious and others will be hereinafter specifically pointed out, this invention consists of certain features of construction and arrangement of parts more fully described in the following 35 specification and shown in the accompanying drawing which forms part thereof, and in which—

Figure 1 is a side elevation of an egg-beater embodying this invention,

40 Fig. 2 is a rear elevation of the beater of Fig. 1,

Fig. 3 is a plan view of the beater of Figs. 1 and 2, and

45 Fig. 4 is a fragmentary view, partly in section, of certain parts of the beater of Figs. 1, 2 and 3.

Referring to Fig. 1,—the strip metal beating elements 21, 21 are journaled upon the frame 22; and the upper ends of said elements extend through and are bent over 50 above openings provided therefor in the pinions 23, 23, which pinions are journaled upon the upper portions of the frame 22.

The body member 24 has a handle 25 55 formed at one end thereof and has lugs 26,

26 formed near the other end thereof for holding the upper ends of the frame 22. The perforated ears 27, 27 are formed from the member 24 and are situated intermediate the handle 25 and the lugs 26, 26, and the shaft 28 is journaled in the perforations of said ears to rotate freely therein.

The driving wheel 29 is fixed upon an end of the shaft 28, and said wheel carries the handle 30 for operation thereof. As best 60 shown by Fig. 4, the shaft 28 has a shoulder 31 from which a reduced diameter portion 32 extends through the washer 33 and the center hole of the wheel 29; said portion 32 being riveted over at 34 outside 70 the wheel 29, so that the teeth 35 of said wheel will be rigidly maintained in a plane perpendicular to the axis of said shaft.

The ears 27, 27 are spaced apart such distance that, when the shaft 28 is journaled 75 therein, the teeth 35 will be maintained in substantial alignment with the major axis of the member 24 notwithstanding the clearance between the shaft 28 and the walls of the perforations in said ears which provides 80 a free running fit therebetween, even when such clearance is augmented by considerable enlargement of such perforations, such as may result from extended use of the beater.

The one of the ears 27 which is situated 85 nearest to the wheel 29 is disposed at such distance outside of the general outline of the member 24 as to provide ample space between the rear face of said wheel and the edge of said member so that such parts may 90 be readily cleansed. The rear end of the shaft 28 is riveted over so as to form a head 36 which is spaced away from the washer 33 a distance slightly greater than that between the outer faces of the ears 27, 25 27; so as to prevent excessive end-chase of the shaft 28, while permitting said shaft to rotate freely.

The diameter of the wheel 29 is such that the teeth 35 thereof will effectively engage 100 those of one of the pinions 23, 23 when the shaft 28 occupies its intended position in the perforations of the ears 27 and the bent-over ends of the elements 21, 21 above said pinions rest against the lower end of the 105 member 24.

The teeth of the wheel 29, and those of the pinions 23, 23, are disposed at an angle of approximately 45° to the faces thereof, and all of said teeth are V-shaped, of a 110

length at least five times the thickness of the sheet metal from which they are cut, and are so positioned that the spaces therebetween are not less than one and one-half 5 times the circumferential area or thickness of said teeth. Because of the shape, the spacing and the disposition of said teeth relative to their axis of rotation, as just described, they roll very freely even when 10 set to mesh more deeply than would be practicable in ordinary spur and bevel gear practice, so that the effectiveness of their operation is not impaired by comparatively wide changes in relative positioning of their 15 centers of rotation; and said teeth act equally well when meshing between gears whose axes of rotation are disposed parallel or at any angle to one another.

The member 24 is twisted between the 20 ears 27, 27 and the handle 25, so that the axis of said handle is disposed at an angle of approximately 60° from the axis of the shaft 28, for a reason which is hereinafter more fully explained.

25 For the larger sizes of egg-beaters, two lugs, such as the lugs 26, are provided for holding each of the ends of the frame 22; for the smaller sizes, it may be considered preferable to employ but one such lug for 30 each frame end. If two lugs are provided for holding each of the frame ends, the material of the frame may be swaged between said lugs, as shown, for the purpose of preventing endwise movement of said frame 35 through the channels provided by said lugs. In any event, such frame ends should be securely fastened in the lugs in some suitable manner. It has been found to be desirable to somewhat swage the portions of 40 the legs of the frame 22 directly below the pinions 23, 23, as at 37 (see Fig. 4), so as to prevent excessive movement of said pinions along the lengths of the legs of said frame away from the end of the member 24.

45 In the use of the beater shown, the handle 25 is encircled by the fingers of one hand of the user, the portion of the body member 24 immediately adjacent to said handle passing between the fingers; and the wheel 50 29 is thus presented for convenient operation by the other hand of the user. The axis of rotation of said wheel will then be substantially in alignment with the arm of the hand of the user which grasps the handle 30 55 and operates the wheel 29. Because of the peculiar arrangement of the teeth of the wheel 29 and of the pinions 23, 23, the beater operates with a minimum of friction and irregularity; and, because of the various 60 features of construction already described, this beater will operate successfully throughout an exceptionally long period of use.

65 It is believed that the construction and use of this invention is so clearly disclosed

by the accompanying drawing and the foregoing description, that those skilled in this art will fully comprehend same, without further description thereof herein.

It should be understood that features of 70 this invention are adapted for use, either singly or in groups comprising less than all of such features, in combinations embodying forms of structure heretofore employed for purposes analogous to other features of this invention.

What I therefore claim and desire to secure by Letters Patent of the United States of America is:

1. In an egg-beater having two beating 80 elements and a U-shaped frame on the respective legs of which said elements are journaled,—the combination of coengaging pinions formed from thin sheet material and journaled upon respective legs of said frame, 85 said pinions each having a cup-shaped toothed periphery so formed as to enable said pinions to effectively serve either as spur or beveled gears, a body member formed from thin sheet material and comprising a tubular T-handle formed by bending a portion of said material so as to provide a hollow cross bar centrally secured to the upper end of said body member, lugs formed integrally from said member by 90 bending portions of said material so as to provide tubular channels, said lugs situated near the opposite end of said body member and enclosing the free ends of said frame, ears formed integrally from said member 95 intermediate said handle and said lugs, a shaft journaled in said ears, a gear formed from thin sheet material and fixed upon said shaft, said gear having teeth formed in the periphery thereof, disposed edgewise and projecting at a suitable angle from the rear face thereof so as to operatively engage the teeth of one of said pinions.

2. In an egg-beater having two beating 100 elements and a U-shaped frame on the respective legs of which said elements are journaled,—the combination of a toothed driving gear and two toothed pinions, said gear and pinions formed from thin sheet material and the length of the teeth thereof being several times the thickness of the material from which they are formed, said teeth disposed edgewise at an angle of approximately 45° to a face of the gear or pinion of which they form part and so that the spaces between adjacent teeth are not less than one and one-half times the area of said teeth, the working faces of said teeth so formed as to provide a V-shaped contour, and a body and handled member to which said gear is journaled and to which the ends of said frame are suitably secured.

3. In an egg-beater having two beating 110 elements and a U-shaped frame on the respective legs of which said elements are 115

- journaled,—the combination of a toothed driving gear and two coengaging toothed pinions, said gear and pinions formed from thin sheet material and the teeth thereof disposed edgewise at an angle of approximately 45° to a face of the gear or pinion of which they form part and so that the spaces between adjacent teeth are not less than one and one-half times the area of said teeth, the working faces of said teeth so formed as to provide a V-shaped contour, and a body and handled member to which said gear is journaled and to which the ends of said frame are suitably secured.
4. In an egg-beater having two beating elements and a U-shaped frame on the respective legs of which said elements are journaled,—the combination of a toothed driving gear and two toothed pinions formed from thin sheet material and the teeth thereof disposed edgewise at an angle of approximately 45° to the face of the gear or pinion of which they form part, the working faces of said teeth so formed as to provide a V shaped contour, a shaft to an end of which said gear is fixed, and the body and handle member having spaced bearings in which said shaft is journaled.
5. As an article of manufacture, a body member for an egg beater having a driving wheel fixed upon a shaft and a pair of parallel guide rods for beater elements, said members being formed from thin sheet material an end of greater width than the remainder of said member rolled over so as to form a tubular centrally supported T-handle, lugs near the other end of said member formed by rolling over the material thereof so as to provide suitably spaced parallel channels for holding the ends of such guide rods, said channels disposed substantially parallel to the length of said member, and perforated ears integrally formed from said member and extending from opposite edges thereof at substantially right angles to a face of said member intermediate said handle and said lugs so as to provide journals for the driving wheel shaft.
6. As an article of manufacture, a body member for an egg-beater having a driving wheel fixed upon a shaft and a pair of parallel guide rods for beater elements, said member being formed from thin sheet metal an end of greater width than the remainder of said body member rolled over so as to form a tubular centrally supported T-handle, lugs near the other end of said member formed by rolling over the material thereof so as to provide suitably spaced parallel channels for holding the ends of such guide rods, said channels disposed substantially parallel to the length of said member, and perforated ears integrally formed from said member and extending from opposite edges thereof at substantially right angles to a face of said member intermediate said handle and said lugs so as to provide journals for the driving wheel shaft.
7. As an article of manufacture, a body member for an egg beater having a driving wheel fixed upon a shaft and a pair of parallel guide rods for beater elements, said member being formed from thin sheet material and comprising a handle at one end thereof, lugs near the other end of said member formed by rolling over the material thereof so as to provide suitably spaced parallel channels for holding the ends of such guide rods, said channels disposed substantially parallel to the length of said member, and perforated ears integrally formed from said member and extending from opposite edges thereof at substantially right angles to a face of said member intermediate said handle and said lugs so as to provide journals for the driving wheel shaft.
8. As an article of manufacture, a body member for an egg-beater having a driving wheel fixed upon a shaft and a pair of parallel guide rods for beater elements, said member being formed from thin sheet material and comprising a handle at one end thereof, lugs near the other end of said member formed by rolling over the material thereof so as to provide suitably spaced parallel channels for holding the ends of such guide rods, said channels disposed substantially parallel to the length of said member, and perforated ears integrally formed from said member and extending from opposite edges thereof at substantially right angles to a face of said member intermediate said handle and said lugs so as to provide journals for the driving wheel shaft.
9. As an article of manufacture, a body member for an egg-beater having a driving wheel fixed upon a shaft and a pair of parallel guide rods for beater elements, said members being formed from thin sheet material, an end of greater width than the remainder of said member rolled over so as to form a tubular centrally supported T-handle, lugs near the other end of said member formed by rolling over the material thereof so as to provide suitably spaced channels for holding the ends of such guide rods, and perforated ears integrally formed from said member so as to provide suitably spaced journals for the driving wheel shaft.
10. As an article of manufacture, a body member for an egg-beater having a driving wheel fixed upon a shaft and a pair of parallel guide rods for beater elements, said member being formed from thin sheet material and comprising a handle at one end thereof, lugs near the other end of said member formed by rolling over the material thereof so as to provide suitably spaced channels for

- holding the ends of such guide rods, and
perforated ears integrally formed from said
member so as to provide suitably spaced
journals for the driving wheel shaft, said
member so formed that the axis of such
shaft will be disposed at an angle of approxi-
mately 60° from the axis of said handle.
11. As an article of manufacture, a body
member for an egg-beater having a driving
10 wheel fixed upon a shaft and a pair of parallel
guide rods for beater elements, said mem-
ber being formed from thin sheet material
and comprising a handle at one end thereof,
and perforated ears integrally formed from
15 said member so as to provide suitably spaced
journals for the driving wheel shaft, said
member so formed that the axis of such shaft
will be disposed at an angle of approxi-
mately 60° from the axis of said handle.

12. In an egg-beater having beating ele- 20
ments and a U-shaped frame on the respec-
tive legs of which said elements are jour-
naled,—the combination of co-engaging pin-
ions formed from thin sheet material and 25
journaled upon respective legs of said frame,
said pinions having slots formed therein
through which the ends of said beater ele-
ments extend, said beater element ends be-
ing bent over above said pinions, a body 30
member secured to said frame ends in posi-
tion to form an abutment for said beater
ends, and projections formed integral from
the legs of said frame below said pinions for
suitably limiting the movement thereof
away from said abutment.

In witness whereof, I hereunto subscribe
my name, this 29th day of April, 1922.

CHARLES E. KAIL.
